CLAIM

Nov. 17, 1993 [WO] WIPO DM/002358

The ornamental design for an intraoral sensor for a dental x-ray apparatus, as shown and described.

[52] **U.S. Cl. D24/158**

DESCRIPTION

[58] **Field of Search D24/158, 176, 186; 433/29, 229; 378/170, 168, 184**

FIG. 1 is a perspective view of an intraoral sensor for a dental x-ray apparatus, showing our new design;

[56] **References Cited**

FIG. 2 is a front elevational view thereof;

U.S. PATENT DOCUMENTS

FIG. 3 is a top plan view thereof;

D. 355,964 2/1995 Nelvig D24/158
1,657,230 1/1928 Simonton 378/170
1,667,442 4/1928 Sikes 378/170

FIG. 4 is a side elevational view of FIG. 2, the left side elevational view being a mirror image;

FIG. 5 is a back elevational view thereof; and,

FIG. 6 is a bottom plan view thereof.
